No. 36,698.

Patented December 22, 1903.

UNITED STATES PATENT OFFICE.

JAMES J. LAWLER, OF MOUNT VERNON, NEW YORK.

DESIGN FOR A CASING FOR GAS-HEATERS.

SPECIFICATION forming part of Design No. 36,698, dated December 22, 1903.

Application filed November 30, 1903. Serial No. 183,294. Term of patent 7 years.

To all whom it may concern:

Be it known that I, JAMES J. LAWLER, a citizen of the United States, and a resident of Mount Vernon, in the county of Westchester and State of New York, have invented a new, original, and ornamental Design for a Casing for Gas-Heaters, of which the following is a specification, reference being had to the accompanying drawings, forming part hereof.

Figure 1 is a front view, Fig. 2 is an end view, and Fig. 3 is a plan view, of the casing.

What I claim as new, and desire to secure by Letters Patent, is—

The ornamental design for the casing of a gas-heater, as shown.

Signed at New York, in the county of New York and State of New York, this 19th day of November, A. D. 1903.

JAMES J. LAWLER.
